UNITED STATES PATENT OFFICE.

ROBERT A. LOWE, OF DULUTH, MINNESOTA, ASSIGNOR OF ONE-HALF TO W. H. LAMSON, OF HINCKLEY, MINNESOTA.

DREDGER-HEAD.

No. 915,454.

Specification of Letters Patent. Patented March 16, 1909.

Application filed April 20, 1908. Serial No. 428,002.

To all whom it may concern:

Be it known that I, ROBERT A. LOWE, of Duluth, St. Louis county, Minnesota, have invented certain new and useful Improvements in Dredger-Heads, of which the following is a specification.

My invention relates to dredger heads adapted for use in connection with a suction pump.

10 The object of the invention is to provide means whereby the dredger head is adapted particularly for work in a bank or on a hard bottom.

15 A further object is to provide a dredger head having a large capacity and one that will be positive in its action and easily operated.

20 The invention consists generally in a dredger head having a nozzle adapted to discharge a jet against the bank or surface where the head is operating.

25 Further, the invention consists in providing a rotary carrier near the mouth of the dredger head.

30 Further, the invention consists in means for directing a jet upon the material directed into the head by the carrier.

35 Further, the invention consists in means for directing a stream against the blades of the carrier.

Further, the invention consists in various constructions and combinations, all as hereinafter described and particularly pointed out in the claims.

40 In the accompanying drawings, forming part of this specification, Figure 1 is a sectional view of a dredger head embodying my invention. Fig. 2 is an outside view of the same illustrating a modification in the position of the pipes on the dredger head. Fig. 3 is a detail sectional view of the dredger head, and, Fig. 4 is a transverse sectional view of the same through the revolving carrier.

45 In the drawing, 2 represents the dredger head having a chamber 3 formed therein which communicates with a large suction pipe 4 leading to a centrifugal pump (not shown). The dredger head is closed on the 50 sides and at one end and has an opening or mouth 5 through which the material passes into the chamber 3. A shaft 6 is mounted in bearings 7 in the wall of the head and carries a revolving carrier 8 having a series of blades 55 which sweep around in the mouth of the

dredger head and direct the material into the chamber 3. This wheel or carrier is arranged to operate slowly, and for the purpose of loosening the material when the machine is operating in a hard bank I provide a pipe 60 9 arranged on the inner or outer surface of the dredger head and terminating in a tapered nozzle 10 which is adapted to direct a jet of water against the surface to be dredged, and loosen the same and direct it into the 65 mouth of the dredger head where it will be caught by the revolving wheel 8. The pipe 9 communicates with a force pump and is adapted to throw a very strong stream of water capable of loosening the gravel in a 70 hard bank or bottom. The force of the stream is increased by providing the tapered nozzle 10. In addition to the pipe 9 I prefer to provide a pipe 11 communicating with a port 12 in the wall of the chamber 3 and in 75 the rear of the wheel 8. This pipe 11 is also connected with the force pump and is intended to supply water to the chamber 3 for the purpose of rendering the material therein of proper consistency to pass to and 80 through the suction pump. This pipe 11 connected with a separate pump from the pipe 9 may be in use or not, as preferred.

A small nozzle 13 is formed in the wall of the chamber 3 and communicates with the 85 pipe 9 and is adapted to direct a stream against the blades of the wheel 8 and keep them clean. The wheel 8 has two functions, one as a carrier and the other as an indicator to aid the operator in determining the amount 90 of material entering the dredger head. In case it is found that an insufficient amount of water is entering the dredger head additional pumps may be attached to the pipe 11 and a larger supply of water taken in.

95 I do not wish to be confined to the form of carrier or wheel illustrated herein as I may use any rotating device adapted to direct the material into the chamber, in combination with one or more jets for loosening the material. I may also increase the number of jets for supplying water to the dredger head chamber. In various other ways the details of my invention may be modified without departing from the spirit thereof.

100 I claim as my invention:—

1. A dredger head having an intake opening and a chamber in the rear of said opening and a nozzle arranged to project a jet against the material in front of said opening and a 110

- suction pipe communicating with said head between said opening and said chamber.
2. A dredger head having an intake opening and a nozzle located on the wall of said head and arranged to project a jet against the material contiguous to said opening and a material carrier arranged to deliver the material through said opening.
3. A dredger head having an intake opening, a suction pipe and a chamber in the rear of said opening and means located near the mouth of said opening for directing the material entering therein to said chamber.
4. A dredger head having an intake opening, and a chamber in the rear of said opening, a suction pipe communicating with said head between said opening and said chamber, and a material carrier located in said head intermediate to said opening and said suction pipe.
5. A dredger head having an intake opening, a material carrier located in said head contiguous to said opening, and a nozzle arranged to direct a jet in front of said opening and said carrier, substantially as described.
6. A dredger head having an intake opening and a chamber in the rear of said opening, a suction pipe communicating with said chamber and a revolving wheel located between said suction pipe and said opening and in front of said chamber.
7. A dredger head having an intake opening, a suction pipe and a wheel having a series of blades provided with flat surfaces and arranged in said opening and extending from side to side thereof, said wheel having a slow revolving movement, substantially as described.
8. A dredger head having an intake opening and a chamber in the rear of said opening, a suction pipe communicating with said chamber, means interposed between said opening and suction pipe for directing the material into said chamber and a nozzle arranged to direct a stream into said head in the rear of said conveying means.
9. A dredger head having an intake opening and a chamber in the rear thereof and a suction pipe communicating with said chamber, a carrier contiguous to said opening for directing the material into said chamber and nozzles having jets arranged to project streams of water in front of and in the rear of said carrier.
10. A dredger head having an intake opening, a carrier having blades located in said head near said opening and a nozzle arranged to direct a stream upon the surfaces of said blades, for the purpose specified.
11. A dredger head having an intake opening, a suction pipe communicating therewith, and a nozzle arranged to direct a stream across said head and lengthwise in said suction pipe, for the purpose specified.
12. A dredger head, having an intake opening and nozzles arranged to project jets in front of and in the rear of said opening.
13. A dredger head, having an intake opening, nozzles arranged to project jets in front of and in the rear of said opening, and a material carrier operating between said nozzles.
14. A dredger head having an intake opening, a suction pipe and a nozzle arranged to project a jet lengthwise in said pipe and a carrier located between said opening and said nozzle.
15. A dredger head, having an intake opening and a chamber in the rear of said opening and a suction pipe communicating with said head, intermediate to said chamber and said opening.
16. A dredger head, having an intake opening, a suction pipe communicating with said head and a material carrier intermediate to said opening and said suction pipe.
17. A dredger head, having an intake opening, a suction pipe communicating with said head, a revolving carrier interposed between said opening and said suction pipe and a driving shaft therefor.
18. A dredger head, having an intake opening, a suction pipe therefor, a driving shaft extending parallel substantially with said suction pipe, and a wheel carried by said driving shaft and operating in said opening.
- In witness whereof, I have hereunto set my hand this 13th day of April 1908.

ROBERT A. LOWE.
